CABINET SINK UNIT

Harry R. Trout and Frederick M. Hill, Pittsburgh, Pa., assignors to American Radiator & Standard Sanitary Corporation, Pittsburgh, Pa., a corporation of Delaware

Application January 2, 1953, Serial No. 22,976

Term of patent 14 years

(Cl. D33—19)

Fig. 1

Figure 1 is a perspective view showing one side and the front of a cabinet sink unit, embodying our new design, and

Figure 2 is an enlarged fragmentary view showing a handle and its adjacent cabinet portion.

We claim:

The ornamental design for a cabinet sink unit, substantially as shown.
